UNITED STATES PATENT OFFICE.

WILLIAM M. SMITH, OF TURTLE CREEK, PENNSYLVANIA.

STAY-BOLT.

932,342.

Specification of Letters Patent. Patented Aug. 24, 1909.

Application filed May 7, 1909. Serial No. 494,692.

To all whom it may concern:

Be it known that I, WILLIAM M. SMITH, a citizen of the United States, residing at Turtle Creek, in the county of Allegheny and State of Pennsylvania, have invented certain new and useful Improvements in Stay-Bolts, of which the following is a specification.

This invention relates to flexible stay bolts and the object thereof is to provide means in a manner as hereinafter set forth for bracing the roof and crown sheets of boiler fire boxes, which will allow for and accommodate the forces of expansion and contraction on lines of least resistance, that will permit of material movement of the complete fire box under expansion and contraction without imparting twisting or bending strains to the stay bolts or the sheets to which the stay bolts are attached and further that will enable the conveniently positioning and securing of the stay bolt at any angle desired with respect to the boiler sheets without the employment of coupling devices or pads attached to the inner face of the boiler sheets.

Further objects of the invention are to provide in a manner as hereinafter set forth a flexible stay bolt for the roof and crown sheets of boiler fire boxes which is capable of being conveniently positioned at the desired angle, flexing when occasion so requires, that is, on the expansion and contraction of the boiler sheets, strong, durable, efficient in its use, readily adjustable for the purpose of decreasing or increasing the length of the bolt and inexpensive to manufacture.

With the foregoing and other objects in view, the invention consists of the novel construction, combination and arrangement of parts hereinafter more specifically described and illustrated in the accompanying drawings, wherein is shown the preferred embodiment of the invention, but it is to be understood that changes, variations and modifications can be resorted to which come within the scope of the claims hereunto appended.

In the drawings, wherein like reference characters denote corresponding parts throughout the several views, Figure 1 is a view in section through the roof sheet of a boiler and crown sheet of a fire box showing the adaptation therewith of flexible stay

bolts in accordance with this invention, Fig. 2 is a sectional detail view showing the roof sheet and the coupling means carried thereby for one end of the bolt, Fig. 3 is a detail view in section of a portion of the crown sheet showing the coupling means employed for connecting the other end of the bolt in position, Fig. 4 is a sectional view in elevation of a modified form of stay bolt in accordance with this invention, and Fig. 5 is a like view of another modified form.

Referring to the drawings in detail, 1 denotes the roof sheet of the boiler, and 2 the crown sheet of the fire box, these are of known construction.

The roof sheet 1 is formed with a series of openings 3 having the walls thereof provided with threads to which are attached coupling plugs referred to generally by the reference character 4. Each of the plugs 4 is cylindrical and hollow from end to end and formed with peripheral threads 5 for engagement with the threads of the walls of the openings 3. Each of the plugs 4 at its inner end is formed with an annular flange 6 which extends at right angles with respect to the body portion of the plug and the said flange 5 has a flat upper face 7, a flat lower face 8, and is flared as at 9. The upper face 7 is of greater width than the lower face 9. The upper face 7 of the flange 6 constitutes a seat for a purpose to be hereinafter referred to. Each of the plugs 6 is furthermore provided with a plurality of openings 10 arranged above the plane of the flange 6 and in a plane inwardly of the inner face of the roof sheet 1. The openings 10 extend downwardly at an inclination and constitute escape ports for any steam which may be generated within the plug and also escape ports for condensates. The plug 4 is closed through the medium of a disk 11, the latter having peripheral threads which engage with threads formed on the inner face of the plug at the outer end thereof. The disk 11 is provided with a groove 12 to receive a suitable tool or instrument for positioning or removing the closure disk 11 when occasion so requires.

Arranged within each of the coupling plugs 4 is an annular bearing member 13 having a flat lower face for engagement with the seat formed by the flat upper face 7 of the

flange 6. The diameter of the member 13 is such as to snugly fit the plug 4, but capable of being shifted upon its seat when occasion so requires. The upper face of the member 13 is beveled as at 14. The member 13 approximately centrally thereof is provided with a bore, the upper portion of the wall of the bore is rounded to provide an annular seat 15, the seat 15 is inclined with respect to the axis of the plug. The function of the seat 15 will be hereinafter referred to. That portion of the wall of the bore below the seat 15 is flared as at 17 to provide a clearance for a purpose to be hereinafter referred to.

The crown sheet 2 is formed with a series of openings 18, the walls of which are threaded and engaging with the said threads are the coupling plugs 19. The coupling plugs 19 are of a length as to project from the inner face of the seat 2 and have their inner ends inturned as at 20 to provide seats 21 for a function to be presently referred to.

The plugs 19 are closed by the disk 22, which has peripheral threads for engagement with the threads on the inner face of the plugs 19. The disk 22 is grooved as at 23 for the reception of a suitable tool or instrument to facilitate the removal and positioning of the disk.

The form of stay bolts shown in Figs. 1, 2 and 3 consist of a shank 24 having the outer end thereof enlarged as at 25 to constitute a head, the head 25 at its outer terminus being squared as at 26 for the reception of the tool to manipulate or adjust the bolt when occasion so requires. The enlarged head 24 is rounded so that its inner portion will constitute the bearing surface which is mounted against a seat 15 formed on the wall of the bore of the annular bearing member 13. The shank 24 at its inner end is threaded as at 27 and engaging the said threads 27 is a removable head 28, the latter being provided with interior threads for engagement with the threads 27 and is furthermore provided with a rounded enlargement 29, the periphery of which constitutes a bearing surface for engagement with the seat 21 of the inner coupling plug 19. The removable head 28 constitutes means whereby the length of the bolt can be increased or diminished when occasion so requires.

The centers of the inner plugs 19 are always on a line with the axes of the bores of the bearing members 13 whereby the bolts can always be set at the desired inclination.

The bore of the bearing member 13 is inclined with respect to the axis of the plug 4, but the direction of inclination of the bore of the bearing member 13, when the said bearing member 13 is in its operative position, is opposite with respect to the direction of inclination of the plug 4, when the latter is mounted in sheet 1.

By setting up the coupling plugs 4 in the manner as stated and with the bearing member 13, the bore of the latter being inclined as stated, it does not necessitate the angularly-disposing of the openings with respect to the coupling plugs so that the bolts can be properly positioned. The openings upon one side of the center of the sheet or upon the other side of the center of said sheet can be disposed at a different angle to that of the inclination of the inner coupling plugs 19, yet the stay bolts can be set up at the proper angle. Such position is obtained owing to the inclined bore of the bearing member 13 and the shifting of the heads 25 and 28 upon the seats 15 and 21 so that the bolts can be readily positioned at the desired inclination and at the same time the necessary degree of flexibility is obtained for the bolts to prevent breakage thereof during the contraction and expansion of the boiler sheets.

By providing the coupling plugs 4 in the manner as stated it is readily apparent that no difficulty is presented when setting up the bolts at varying inclinations, as the bearing members 13 can be readily turned to position the bore thereof to extend in the direction desired, the bolt, with head 28 removed, inserted through the plug and bearing member, the threaded end of the shank then extended into the plug 19 and the head 28 replaced upon the threaded end of the shank 24, thus maintaining the bolt in position and by means of the plugs 4 and 19 and the bearing members 13 the bolts are coupled to the sheets 1 and 2. Prior to the positioning of the head 28 upon the threaded end of the shank, the shank of the bolt is adjusted to the desired inclination, the head 25 and seats 15 and 21 allowing for such adjustment. The beveled end 17 of the wall of the bearing member 13 as well as the beveled inner edge 17^a of the plug 19 allows of the shank 24 of the bolt to be shifted when the heads move upon their seats due to the contraction and expansion of the sheet, that is to say, the beveled or flaring ends 17 and 17^a provide clearances to allow of the movement of the shank, such arrangement affording the necessary flexibility but preventing the breaking of the bolts.

In the construction shown in Fig. 4 the bolt is the same as that referred to in connection with Figs. 1, 2 and 3. The plug and bearing member for coupling one end of the bolt to sheet 1 is the same as that referred to in connection with the Figs. 1, 2 and 3. The plug and bearing member for coupling the bolt to sheet 2 is of a construction similar to that employed for coupling the bolt to sheet 1. The reference characters for the coupling plugs shown in Fig. 4 are the same as that shown in Fig. 2.

In the construction shown in Fig. 5 the

shank of the bolt is indicated by the reference character 30, and is threaded at each end as at 31, 32. Upon the end 32 is mounted a removable head 33 of the same construction as that disclosed in Fig. 3 and upon the threaded end 31 is mounted a removable head 34 also of the same construction as that shown in Fig. 3. The plug and bearing member for coupling that end of the bolt which is provided with a head 33 is the same construction as that disclosed in Fig. 2, the same reference characters being applied. The plug for coupling that end of the bolt provided with a head 34 to the sheet 2 is indicated by the reference character 35 and is provided with peripheral threads 36 whereby the plug can be connected to the screw-threaded wall of the opening in the sheet 2. The plug 35 has its inner face near its inner end of reduced diameter as at 37 to provide a curvilinear seat 38 for the head 34 and the inner face of the plug at its inner end is flared as at 39 to form a clearance for the shank when the bolt shifts. The seat 38 is curvilinear throughout. The plug 35 is closed by a removable disk 40 which is formed with peripheral threads for engagement with the threads on the inner face of the plug 35 at its outer end. By setting up the stay bolts in the manner as heretofore set forth, it is evident that no difficulty is presented in adapting them to portions of the roof sheets and crown sheets where the coupling plugs which are secured into the curved roof sheet will extend at an angle with respect to the bolt, as it is obvious that the plugs can be readily connected to the roof sheet, adjusted if necessary, and the bolt inserted and conveniently positioned to the desired angle.

ing a flat lower face, a flat upper face inclined with respect to the lower face and having a bore, said bore having its upper portion projecting inwardly to provide an annular seat, said seat disposed at an inclination with respect to the axis of the plug, said bore having the lower portion of its wall flaring, and a stay bolt provided with a head, said head mounted upon said seat, said plug further provided in the body portion thereof with a plurality of openings extending downwardly at an inclination.

3. In combination a coupling plug adapted to be secured to a boiler sheet normally to the surface of the sheet at the point where inserted, said plug at its inner end having a right angularly-disposed inwardly-extending annular flange, a bearing member mounted upon said flange, said bearing member having a flat lower face a flat upper face inclined with respect to the lower face and having a bore, said bore having its upper portion projecting inwardly to provide an annular seat, said seat disposed at an inclination with respect to the axis of the plug, said bore having the lower portion of its wall flaring, a stay bolt provided with a head, said head mounted upon said seat, said plug further provided in the body portion thereof with a plurality of openings extending downwardly at an inclination, and means for closing the outer end of the plug.

4. The combination with a roof sheet of a boiler and the crown sheet of a fire box, of coupling plugs secured in the roof sheet normally to the surface of the sheet at the point where inserted and each provided at its inner end with a right angularly-disposed inwardly-extending annular flange, a bearing member mounted upon said flange and hav-

What I claim is:

1. In combination a coupling plug adapted to be secured to a boiler sheet normally to the surface of the sheet at the point where inserted, said plug at its inner end having a right angularly-disposed inwardly-extending annular flange, a bearing member mounted upon said flange, said bearing member having a flat lower face, a flat upper face inclined with respect to the lower face and having a bore, said bore having its upper portion projecting inwardly to provide an annular seat, said seat disposed at an inclination with respect to the axis of the plug, said bore having the lower portion of its wall flaring, and a stay bolt provided with a head, said head mounted upon said seat.

5. The combination with a roof sheet of a boiler and the crown sheet of a fire box, of coupling plugs adapted to be secured to the

2. In combination a coupling plug adapted to be secured to a boiler sheet normally to the surface of the sheet at the point where inserted, said plug at its inner end having a right angularly-disposed inwardly-extending annular flange, a bearing member mounted upon said flange, said bearing member having a flat lower face, a flat upper roof sheet normally to the surface of the sheet at the point where the plugs are inserted and each plug provided at its inner end with a right-angularly disposed inwardly extending annular flange, a bearing member mounted upon said flange, said bearing member having a flat lower face, a flat upper

face inclined with respect to the lower face and having a bore, said bore having its upper portion projecting inwardly to provide an annular seat, said seat disposed at an inclination with respect to the axis of the plug, said bore having the lower portion of its wall flaring, stay bolts provided with heads at each end, the heads at one end mounted upon

said seats, and coupling means secured to the sheet for the other heads of the bolts.

In testimony whereof I affix my signature in presence of two witnesses.

WILLIAM M. SMITH.
